**A. FOUTS.
DUMPING VEHICLE.**

(Application filed Oct. 18, 1901.)

(No Model.)

UNITED STATES PATENT OFFICE.

ALBERT FOUTS, OF ALEXANDRIA, INDIANA, ASSIGNOR OF ONE-HALF TO
HARVEY A. MOORE, OF INDIANAPOLIS, INDIANA.

DUMPING-VEHICLE.

SPECIFICATION forming part of Letters Patent No. 700,318, dated May 20, 1902.

Application filed October 18, 1901. Serial No. 79,064. (No model.)

To all whom it may concern:

Be it known that I, ALBERT FOUTS, a citizen of the United States, residing at Alexandria, in the county of Madison and State of Indiana, have invented a new and useful Dumping-Vehicle, of which the following is a specification.

My invention relates to an improvement in means for supporting and operating the bottom sections of that class of dumping-vehicles in which the bottom is composed of a plurality of swinging sections.

The object of my invention is to provide improved mechanism for supporting the swinging bottom sections in a device of the character described of such character that the weight of the load will not be carried by the fastening means, yet such that the swinging sections may be easily operated and a load quickly and readily dumped.

The accompanying drawings illustrate my invention as applied to a dumping-wagon.

Figure 1 is a side elevation with the bottom sections in receiving position. Fig. 2 is a side elevation with the parts in dumping position. Fig. 3 is a section on line 3 3 of Fig. 1.

In the drawings, 5, 5, &c., indicate a series of bottom sections which are hinged upon parallel axes to a bed 6, which may take the form of a wagon, car, or other vehicle. These bottom sections may be arranged either transversely or longitudinally of the bed, and in the drawings each of said sections is shown as provided at each end with a strengthening angle-iron 7, having near one end a socket 7', adapted to receive a pintle 8, carried by the lower end of the bracket 9, bolted to the side of the bed 6. Pivoted to the forward end of each section 5 is a lever 10, the lower end of which is pivoted to the free end of a link 11, pivoted at 12 to the bed. The upper or opposite ends of the several levers 10 are connected by a bar 13, which in turn is attached to a link 14, pivoted to seat-frame 15, pivoted at 16 to the bed 6. Any desired means may be provided for holding the seat in its normal position—as, for instance, a locking-bar 17, pivoted at 18 to the bed and provided with a pin 19, adapted to be passed into a notch 20, carried by a portion of the seat.

For the sake of strength it is desirable that

the levers 10, links 11 and 14, and bar 13 be in pairs on opposite sides of the bed. The form and arrangement of levers 10 and their adjacent links 11 is such that when the seat is thrown into its normal position, as shown in Fig. 1, the fulcrum of each lever 10 on the adjacent section 5 will lie substantially in a line with the then positions of the pivotal point in the link 11 and its point 12 of attachment with the lever 10. The arrangement and form should also be such that the line between the pivot and the end of each link 11 is such as to be substantially at right angles to the normal position of the sections 5. By this arrangement any weight placed upon the sections 5 will exert a direct pull upon the links 11, and there will be substantially no stress upon the levers 10 tending to shift their positions. As a consequence but little stress is exerted by the load upon the means which holds the levers from accidental displacement, and a very slight upward force upon the seat after the removal of the locking-bar will release the parts, so that any weight upon the sections 5 will tend to swing said sections downward, and thus be forced to drop from the bed.

It will be readily understood that any means other than the pivoted seat may be used to hold the several levers 10 from displacement without departing from my invention.

I claim as my invention—

1. In a dumping-vehicle, the combination with the body, of a swinging section forming a portion of the bottom thereof, a lever pivoted between its ends to the free end of said section, a link pivoted upon the body and having pivotal connection with one end of said lever, and means for swinging said lever.

2. In a dumping-vehicle, the combination with the body, of a plurality of swinging sections forming the bottom thereof, a plurality of levers each pivoted between its ends to the free end of one of said sections, a plurality of links pivoted upon the body and each pivotally connected to one end of a lever, a bar connecting the opposite ends of all the levers, and means for shifting said bar.

3. In a dumping-vehicle, the combination with the body, of a plurality of swinging sections forming the bottom thereof, a plural-

- ity of levers each pivoted between its ends to the free end of one of said sections, a plurality of links pivoted upon the body and each pivotally connected to one end of a lever, a bar connecting the opposite ends of the levers, a seat pivoted upon the body, a connection between said seat and the bar, and means for holding said seat in its normal position.
- 10 4. In a dumping-vehicle, the combination with the body, of a plurality of swinging sections forming the bottom thereof, a plurality of levers each pivoted between its ends to the free end of one of said sections, a plurality of links pivoted upon the body and each having a pivotal connection with one end of an adjacent lever, and means for swinging said levers simultaneously, the arrangement being such that when the sections are thrown
- 15 into alinement the pivotal point of a link, its point of connection with its lever, and the point of connection of said lever with its section will lie in a substantially straight line.
5. In a dumping-vehicle, the combination with the body, of a plurality of swinging sections forming the bottom thereof, a plurality of levers each pivoted between its ends to the free end of one of said sections, a plurality of links pivoted upon the body and having a
- 20 pivotal connection with one end of the adjacent lever, the arrangement being such that when the sections are thrown into alinement the pivotal point of the link, its point of connection with its lever, and the point of connection of said lever with its section will lie
- 25
- 30
- 35

in a substantially straight line, a bar connecting the opposite ends of all of the levers, a seat pivoted upon the body, and a link connecting said seat and bar, substantially as and for the purpose set forth.

40

6. In a dumping-vehicle, the combination with the body, of a plurality of swinging sections forming the bottom thereof, a plurality of levers each pivoted to the free end of one of said sections, a plurality of links pivoted upon the body and each having a pivotal connection with an adjacent lever, and means for swinging the said levers simultaneously, the arrangement being such that when the sections are thrown into alinement the pivotal point of each link, its point of connection with its lever, and the point of connection of said lever with its section will lie in a substantially straight line.

50

7. In a dumping-vehicle, the combination with the body, of a swinging section forming a portion of the bottom thereof, a lever pivoted to the free end of said section, and a link pivoted upon the body and having a pivotal connection with said lever, the arrangement being such that when the swinging section is in normal position the pivotal point of the link, its point of connection with the lever, and the point of connection of said lever with the section will lie in a substantially straight line.
